UNITED STATES PATENT OFFICE.

WILLIAM HENRY ILLINGWORTH, OF HALIFAX, ENGLAND.

ELECTRICAL CUT-OUT.

1,316,095.

Specification of Letters Patent. Patented Sept. 16, 1919.

Application filed November 13, 1918. Serial No. 262,399.

To all whom it may concern:

Be it known that I, WILLIAM HENRY ILLINGWORTH, a subject of the King of Great Britain, residing at 1 Ruskin Terrace, Lee 5 Mount, Halifax, in the county of York, England, have invented certain new and useful Improvements in Electrical Cut-Outs, of which the following is a specification.

This invention relates to an electrical cut-out and has for its chief object to produce an appliance which will be simple and more efficient than the ordinary cut-out, or fuse and be free from their objections.

Among these objections are arcing with its 15 resulting injuries such as fused terminals, broken bases and the like. A sudden surge of current produced by breaking of the circuit, or blowing of the fuse owing to a dead short circuit. Inconstancy in the action of 20 a cut-out or fuse wire and injuries or fires produced by the substitution for the correct wire of a thicker fuse wire, or of one having a higher fusing point.

In overcoming these objections I employ 25 a cut-out of the kind in which a column of mercury or other liquid (hereinafter referred to as mercury) forms an electrical connection between two contacts but parts at some portion of its length when the current 30 reaches a predetermined amperage.

According to this invention the upper end of the column is arranged in open communication with the atmosphere and a well so placed or arranged that immediately the column parts the whole of the mercury above the point of separation is discharged into the well and provides a free space for the gas or vapor generated by the parting of the column to escape to the atmosphere. The column is made larger in cross sectional area toward the ends to insure its parting midway or at any other predetermined point between the contacts other than immediately beneath the top and immediately above the bottom contact.

A feature of the invention consists in so constructing the appliance that the electrical connection can instantly be restored by tilting the apparatus so that the mercury runs from the well to the column. This may be effected by forming the aforesaid well or pocket at one side of the upper end of the column and making it large enough to contain more mercury than is sufficient to 55 fill the column. This well or pocket is ar-

ranged in line with the contacts and the lower contact blade may be pivoted to a contact or terminal on an insulated base, the arrangement being such that by tilting the carrier to disconnect the upper contact from the corresponding terminal on the insulated base, the mercury in the well, or a portion of it flows back and re-forms the column, thereby reestablishing the electrical connection between the upper and lower contacts. 60 In practice it is found that a small amount of gas is generated during the parting of the column and to allow the escape of such gas a vent is formed in the carrier above the well. When a column of small diameter is employed 65 for currents of low amperage, auxiliary means are employed for drawing or forcing the mercury into the carrier to make and re-make the column. This auxiliary means may comprise a pump which may be situated 70 either at the top, or at the bottom of the carrier, and be actuated by hand, or automatically during the tilting of the carrier. When a current of heavy amperage is employed 75 two or more columns of mercury may be arranged in parallel and a preferred construction consists in arranging the ends of the columns to converge to a single aperture or passage at one or both ends of the carrier. The passage or passages for the column or columns may be formed in an interchangeable core or in the carrier itself. If 80 desired an indicator may be used in connection with the appliance to show whether the circuit is broken or unbroken and such indicator may be actuated by the aforesaid gas or by variation in the level of mercury in the 85 well.

In the accompanying drawings:

Figure 1 is a vertical section of an electrical cut-out operating on the principle of this invention and shown in hinged connection with an insulated base.

Fig. 2 is a front elevation of the carrier shown partly in section.

Fig. 3 shows the appliance in its resetting position.

Fig. 4 is a plan of the top cover.

Fig. 5 is an inverted plan of the top cover.

Fig. 6 is a plan of the carrier with the 105 top cover removed.

Fig. 7 is a section taken approximately on line 7-7 of Fig. 1.

Fig. 8 is a plan and Fig. 9 an inverted plan of the bottom cover.

Fig. 10 is a section showing a pump applied to the bottom cover.

Fig. 11 is a section of a solid top contact.

Fig. 12 is a section and Fig. 13 an end view of a core having passages arranged in parallel.

Fig. 14 is a diagram of a form of indicator adapted to be actuated by the displacement of mercury.

10 A indicates the column of mercury, B the carrier, C, C¹ the two contacts, D the well or pocket.

The carrier B may be constructed from porcelain or other appropriate material and

15 is provided at its ends with two detachable caps b b¹ which make a fluid tight joint with the body of the carrier through the intervention of packing b². Extending through the cap b are two vent passages d

20 which form a communication between the top of the well D and a pocket or recess d¹ hereinafter referred to. The body of the carrier contains a core E which may be constructed from cement, fireclay, porcelain, 25 silica, or other suitable material. This core may constitute a permanent part of the carrier or it may be detachable as shown, a tight joint between the carrier and core being made by packings e e¹. By making the

30 cores interchangeable a very wide range is given to the apparatus as the same can be used for currents varying from say 5 to 1000 amperes by merely substituting one core for another. Extending through the core is a 35 passage for the column of mercury A, the smallest cross sectional area of such passage determining the amount of current that will pass before causing the column to part. This portion is advantageously arranged

40 midway between the ends of the column as shown in Fig. 1. The upper and lower ends of the passage are advantageously slightly countersunk to form two shallow basins e² which become filled with mercury and 45 afford a good contacting surface with the upper and lower contacts C C¹. In the example shown these contacts comprise spring pressed plungers slidably mounted in sockets c c¹ which are attached to the covers

50 b b¹ respectively. The nuts c^x which retain the contacts C C¹ in their respective sockets are preferably constructed from material possessing no affinity for mercury. The spring of the lower contact is made stronger 55 than the spring for the upper one to retain the core in position against its packing e. The upper contact C is cut away at e² to form a free passage for the mercury to and from the well D and the latter may be

60 formed with a spout or channel d² to facilitate such passage. This passage is made as large as possible to prevent any choking action of the mercury when the column parts and in order that the whole of the mercury above the point of separation may be de-

flected or thrown over into the well the cut away portion in the top contact is advantageously shaped as shown at c² in Fig. 11. Projecting from the sockets c c¹ are contact blades c³ c⁴ which extend through the side 70 of the caps, the blade c⁴ being detachably hinged to a contact c⁶ on an insulated base c⁷ and the upper blade c³ being adapted to be slid into and out of engagement with a spring contact c⁸ on the said base. To utilize 75 the apparatus it is charged with mercury until the column is completely filled and the mercury overflows a little into the well. In this condition an electrical connection is established between the upper and lower contacts by the column of mercury as soon as the top cover b is placed in position. If a heavier current than the apparatus is designed for passes through it, it causes a portion of the mercury in the column to be discharged into 80 the well and the column ultimately vaporizes and parts at the portion of smallest cross sectional area with the result that the circuit is broken. When this takes place a slight discharge of gas escapes by way of 85 the vent passages d d and such gas may be used to actuate an indicator to show that the circuit is broken. To restore the electrical connection between the contacts, all that is necessary is to tilt the carrier to the position 90 shown in Fig. 3, so that a portion of the mercury in the well returns and refills the column and basin above the point of separation, the well being large enough to retain an excess quantity of mercury to provide for 95 any shrinkage or loss which may take place during the continued working of the apparatus. If the core passage is too small for the mercury to pass down by gravity a pump is used. In Fig. 1, a piston F works in a recess 100 or cylinder f in the contact C and is normally retained in its raised position by a spring f¹ which encircles the upper end of the piston rod f². In this arrangement the carrier is tilted to fill the space above the 105 core E with mercury and the piston is then actuated to force the mercury down the core passage until the latter is filled.

In the modification shown in Fig. 10, a plunger F¹ is mounted in the bottom contact C¹ and passes through a gland f³ and stuffing box f⁴. The pump parts are constructed from any suitable material which will not possess an affinity for mercury. If no pump is employed, or if it is applied to 115 the bottom contact a solid top contact such as that shown in Fig. 11, would be used. For heavy currents the core E may be formed with two or more passages arranged in parallel and in the example shown in 120 Figs. 12 and 13 the core is formed with four passages e³. To insure all the passages being completely filled when the carrier is tilted, the passages are arranged to converge to a single opening e⁴ at the upper 125 130

or filling end, the lower portions of the passages being parallel. The converging and parallel passages are reduced in cross sectional area toward the center of the core to bring the point of highest resistance midway between the ends of the core.

In Fig. 14, G is an indicator adapted to be operated by displacement of mercury in the well D. In the example shown the indicator 10 comprises a two armed lever pivoted near one end to a light frame g having two legs g¹ connected by a cross piece g² and a third leg g³ to a float g⁴. The latter rests on the surface of the mercury in the well and when 15 the level of the mercury rises owing to the column parting, the float, frame and lever are lifted bringing the short arm of the lever against an abutment g⁵ on a strap g⁶ which forms part of an attachment for the top 20 cover b with the result that the lever is tilted until its long arm projects above the top of the cover b and indicates that the circuit is broken.

In the case of a distribution board, a number 25 of carriers would be separately mounted on a base or bases and take the place of the ordinary fuses and carriers. For certain classes of work the carrier may be armored or inclosed in a metal box.

30 By the invention described the circuit is broken without arcing and without any surge of current. The circuit is always broken by the exact amount of current for which the apparatus is set with the result 35 that its action is absolutely constant. The apparatus is entirely foolproof and cannot be tampered with to make it take a heavier current than it is designed for. No replacements are required and all fuse wires are 40 done away with. The apparatus can be used in place of the movable contacts on the ordinary double pole switch by using two carriers linked together.

What I claim as my invention and desire 45 to secure by Letters Patent in the United States is:-

1. In an electrical cut out, the combination of an upper contact cap provided with a socket, a lower contact cap also provided 50 with a socket, means engaging said sockets and containing sufficient mercury to provide an electrical connection between said contacts, an overflow to receive the mercury thrown by vaporization when the connection 55 is broken and an air vent in one of said caps for the free escape of vapor produced by the said breakage.

2. In an electrical cut out the combination of an upper contact cap provided with a 60 socket, a lower contact cap also provided with a socket, a core engaging said socket and provided with a plurality of mercury-containing passages providing mercurial columns in parallel between said contacts, an 65 overflow to receive a portion of the mercury

from the columns when broken by vaporization, and an air vent in one of said caps for the free escape of vapor.

3. In an electrical cut-out, the combination of an upper contact, a lower contact, a core 70 provided with a passage communicating with said contacts, said passage having a reduced cross sectional area at some predetermined point between its ends, an overflow situated in free communication with the upper end of the passage, an air vent arranged in open communication with the passage and overflow, and a body of mercury adapted to fill the said passage and make an electrical connection between the said contacts. 75

4. In an electrical cut-out, the combination of a top contact having a curved deflecting surface, a bottom contact, a passage connecting same with the top contact, an overflow arranged in free and open communication 85 with the deflecting surface of the top contact, an air vent arranged in open communication with the passage, and a body of mercury adapted to fill the said passage and make an electrical connection between the 90 said contacts, said deflecting surface being positioned to deflect mercury into said reservoir as it flows from said passage when a blow out takes place.

5. In an electrical cut-out, the combination of an upper contact, a lower contact, means for establishing an electrical connection between said contacts by a column of mercury, an overflow to receive mercury thrown over by vaporization of a portion of 100 the column, an air vent for free escape of vapor, and an indicator actuated through the breaking of the connection to show when the circuit is broken and unbroken. 95

6. In an electrical cut-out, actuated by 105 the breaking of a column of mercury, a detachable core having a longitudinal passage with a reduced cross sectional area at some predetermined portion of its length between its ends. 110

7. In an electrical cut-out actuated by the breaking of a column of mercury, a detachable core having a plurality of longitudinal circuit-maintaining passages communicating 115 with a single opening.

8. In an electrical cut out actuated by the breaking of a column of mercury, a detachable core having a plurality of longitudinal circuit-maintaining passages each of which is reduced in cross sectional area at some portion of its length, all of said passages communicating with a single opening. 120

9. In an electrical cut out actuated by the breaking of a column of mercury, means for pivotally supporting the cut out element at 125 one end, and means whereby the tilting of said element upon its pivotal support will remake the column.

10. In an electrical cut-out actuated by the breaking of a column of mercury between 130

- two contacts, a carrier provided with two contacts having laterally projecting blades, a passage communicating with said contacts for the column of mercury, a well situated at one side of the upper end of the passage and in open communication therewith, an air vent arranged in open communication with the well, an insulated base provided with two contacts respectively arranged in hinged and sliding connection with the contact blades, the relative positions of the well, contact blades and hinge being such as to cause mercury to flow from the well into the passage and reform the column when the carrier is tilted.
11. In an electrical cut-out actuated by the breaking of a column of mercury between two contacts, a carrier provided with two contacts having laterally projecting blades, a passage communicating with the said contacts for the column of mercury, a well situated at one side of the upper end of the passage and in open communication therewith, an air vent arranged in open communication with the passage, an insulated base provided with two contacts respectively arranged in hinged and sliding connection with the contact blades, the relative positions of the well, contact blades and hinge being such as to cause mercury to flow from the well to a recess above the top of the passage when the carrier is tilted and means for mechanically causing the mercury to pass through the passage and make the column.
12. In an electrical cut-out actuated by the breaking of a column of mercury between two contacts, a carrier provided with two contacts having laterally projecting blades, a passage communicating with said contacts for the column of mercury, a well situated at one side of the upper end of the passage and in open communication therewith, an air vent arranged in open communication with the passage, an insulated base provided with two contacts respectively arranged in hinged and sliding connection with the contact blades, the relative positions of the well, contact blades and hinge being such as to cause mercury to flow from the well into the passage and reform the column when the carrier is tilted.

the well into the passage and reform the column when the carrier is tilted, and an indicator actuated by the breaking of the circuit to show when the circuit is broken and unbroken.

35

13. In an electrical cut-out actuated by the breaking of a column of mercury between two contacts, a carrier provided with two contacts having laterally projecting blades, a passage communicating with said contacts for the column of mercury, a well situated at one side of the upper end of the passage and in open communication therewith, an air vent arranged in open communication with the passage, an insulated base provided with two contacts respectively arranged in hinged and sliding connection with the contact blades, the relative positions of the well, contact blades and hinge being such as to cause mercury to flow from the well to a recess above the top of the passage when the carrier is tilted and means for mechanically causing the mercury to pass through the passage and make the column.

In testimony whereof I affix my signature 55 in presence of two witnesses.

WILLIAM HENRY ILLINGWORTH.
